UNITED STATES PATENT OFFICE.

JOSEPH E. BOHNER, OF ANSONIA, CONNECTICUT.

DESIGN FOR A FRAME FOR TABLE-TOPS.

SPECIFICATION forming part of Design No. 24,424, dated June 25, 1895.

Application filed May 11, 1895. Serial No. 549,010. Term of patent 3½ years.

To all whom it may concern:

Be it known that I, JOSEPH E. BOHNER, a citizen of the United States, residing at Ansonia, in the county of New Haven and State 5 of Connecticut, have invented and produced a new and useful Design for Table-Top Frames and Similar Articles, of which the following is a full and complete specification, reference being had to the accompanying drawing, which illustrates the design.

The design consists of a metallic strip or frame of rectangular shape in general form, which constitutes the frame of a table top. In the drawing, one side of two corners of the 15 frame is shown, it being understood that the other parts of the frame bear the same design. It is also to be understood that the frame usually is designed to inclose a table top of wood, onyx, marble or other material artistic to the 20 eye.

The design consists of a frame composed

of the inner edge piece A and of the outer edge piece or strip B. Between these edge pieces and along the sides of the frame are arranged the conventionalized leaf scrolls C 25 and D D arranged in pairs as shown, and which pairs are duplicated to any desired extent. At the corners of the frames are located the ovoidal disks E, and between the pairs of scrolls D and on the outer strip are located the nodules F.

The essential features of the invention are those above set forth.

What is claimed as new is—

The design for the frame of table tops and similar articles, substantially as shown and described.

JOSEPH E. BOHNER.
